UNITED STATES PATENT OFFICE.

CARL FREDRIK HOLMBOE, OF RIS, VESTRE AKER, NORWAY, ASSIGNOR OF ONE-HALF
TO DE NORDISKE FABRIKER DE-NO-FA, OF OSLO, NORWAY.

ELECTRODE FOR ELECTROLYTIC DECOMPOSITION APPARATUS.

Application filed October 1, 1925, Serial No. 59,791, and in France July 4, 1925.

The present invention relates to the type of electrodes which are composed of ribs fastened together so as to form a rigid frame. Electrodes of this type are described and shown in the U. S. A. patent specification No. 1,548,840.

According to the present invention the efficiency of the ribs are increased by providing the central part of the ribs with angle pieces or finlike projections so that this part of the electrodes is brought nearer to a parallel arranged electrode of opposite polarity, whereby the electrolytical resistance of the entire system becomes considerably reduced.

15 The invention is illustrated by way of examples in the accompanying drawing in which Figs. 1, 2 and 3 show an embodiment of the electrode in longitudinal sectional, cross sectional and plan views respectively.

20 Figs. 4, 5 and 6 show a modified embodiment of the electrode.

In the illustrated examples the electrode is composed in substantially the same manner as shown in the above mentioned patent specification. Ribs—plate strips—3 of iron or other suitable metal are threaded upon a number of bolts 1 and are held in the desired distance from one another between the end pieces 4 by means of tube pieces 2 which 25 alternately with the plate strips 3 are threaded upon the bolts.

In the example shown in Figs. 1, 2 and 3 the current supply is arranged in the same manner as shown in the above mentioned 30 patent specification—by means of plates 6 and bolts 10 secured to and insulated from the cover 7.

The ribs 3 consisting of sheet metal carry wings or fins 11 which are formed by cutting and bending outwards the central parts 35 of the sheet ribs between the bolts.

Between the ribs are placed the diaphragms 9 secured to the gas collecting bells 8 on the cover 7 of the electrolyzer 40 vessel. The current supply takes place by means of plate pieces 6 and spindles 10 as

according to the above mentioned prior patent specification.

In the example illustrated on Figs. 4, 5 and 6 the current is supplied to the end pieces 4, which are provided with paws 12 which are fastened to the walls 14 of the electrolyzer vessel. The walls in this case must be conductors. The current then passes from these walls through the angle pieces 55 13, the paws 12 and the end pieces 4 to the bolts 1, and from these latter to the ribs 3 with fins 11.

I claim:

1. An electrode for electrolytic decomposition apparatus, comprising a plurality of interspaced, interconnected conductors provided at their central portions, with projections extending laterally from the conductors, and substantially coextensive with the length of said conductors.

2. An electrode of the class described, comprising a plurality of interspaced, interconnected ribs having projections thereon formed by slitting the central portion of 70 said ribs horizontally and vertically, and bending outwardly the portion so slitted.

3. An electrode of the class described, comprising a plurality of interspaced, interconnected ribs having lateral projections 75 thereon; a plurality of spacing pieces between said ribs; and a plurality of bolts passing through said spacing pieces and said ribs, and binding said members into a rigid frame, substantially as described.

4. An electrode for electrolytic decomposition apparatus, comprising a plurality of interspaced conductors; and means for binding said conductors and said spacing members into a rigid frame work, said binding 85 members being electrically connected to said conductors and to the paraelectric walls of said electrolyzing apparatus.

In testimony that I claim the foregoing as my invention, I have signed my name. 90

CARL FREDRIK HOLMBOE.
